C. S. BUSHNELL.
RAILWAY TRAFFIC CONTROLLING SYSTEM.
APPLICATION FILED APR. 14, 1917.

1,299,295.

Patented Apr. 1, 1919.

UNITED STATES PATENT OFFICE.

CHARLES S. BUSHNELL, OF SYDNEY, NEW SOUTH WALES, AUSTRALIA, ASSIGNOR TO
GENERAL RAILWAY SIGNAL COMPANY, OF GATES, NEW YORK, A CORPORATION OF
NEW YORK.

RAILWAY-TRAFFIC-CONTROLLING SYSTEM.

1,299,295.

Specification of Letters Patent.

Patented Apr. 1, 1919.

Application filed April 14, 1917. Serial No. 161,971.

To all whom it may concern:

Be it known that I, CHARLES S. BUSHNELL, a citizen of the United States, and a resident of the city of Sydney, State of 5 New South Wales, Commonwealth of Australia, have invented a new and useful Railway-Traffic-Controlling System, of which the following is a specification.

This invention relates to a railway traffic 10 controlling system and particularly to such a system wherein switches and signals are electrically controlled from a remote point or distant station.

One of the principal objects of the invention 15 is to provide a means for electrically controlling, from a remote point or station, the operation of a railway switch, the signal governing said switch, and the signals governing the track section in which said 20 switch is located.

A further object of the invention is to obtain the above mentioned object and to further provide a means for indicating, at said 25 remote point or station, the operated condition of said switch and said signals.

Other objects and advantages will appear 30 as the description of the invention progresses, and the novel features of the invention will be particularly pointed out in the appended claims.

In describing the invention in detail, reference is had to the accompanying drawing, wherein I have illustrated a preferred physical embodiment of my invention, and 35 wherein like characters of reference designate corresponding parts.

The single figure is a diagrammatic view 40 of a portion of a stretch of single track adjacent to a siding, and shows the signals, controlling devices and controlling circuits therefor. A tower or operating station is also diagrammatically shown in the figure located at a point remote from said siding and said signals, and having located therein 45 means for controlling said circuits and means for indicating the operations of said control devices and said signals. All of the above mentioned devices and circuits therefor constitute a practical system for the control 50 of an outlying switch from a remote point or station.

Referring to the accompanying drawing, the two rails 1 and 2 adjacent to the siding S are divided by insulating joints 3 into a

series of track sections *a*, *b*, *c*, and *d* of 55 which there are shown two complete track sections, *b* and *c* with end portions of the two adjacent track sections, *a* and *d*. Each of these track sections has a track battery 4 connected across the track rails 1 and 2 60 at one end of said sections, whereas at the other end of said sections, track relays 5 and 6 are connected. The track battery 4 and the track relay of each of said track sections, together with the track rails there- 65 of, constitute the well known normally closed track circuit, the operation of which will be clearly understood by those skilled in the art, without further description. The rails 1¹ and 2¹ of the siding S are also 70 divided by insulating joints 3¹ and are connected in the well known manner to the rails 1 and 2 of the track section *c* being included in the track circuit for the said track section *c*, for the control of the track 75 relay 6. The traffic over this stretch of single track may be considered as in the direction indicated by the arrow *e*.

At the righthand end of the track section *c* is located a signal 7 having two arms 7¹ 80 and 7², the upper arm 7¹ of which governs traffic in the direction indicated by the arrow *e* over the main stretch of track, while the lower arm 7² governs traffic in the direction mentioned over the siding S. At the 85 righthand end of the track section *a* is located a signal 8 for governing traffic in the direction indicated by the arrow *e* over the said track section *a*.

The signals illustrated are of any well 90 known type of semaphore signal and it is considered that a brief description of the same will be sufficient for a clear understanding of the operation and principle thereof, since it is obvious that this invention is in no wise dependent upon the particular character of signals used. This type of signal primarily comprises an operating motor of appropriate construction for moving the semaphore from a biased position, 95 which may be termed the stop or danger position to one or more operated positions; and further comprises means to retain the semaphore in its operated position or positions. In the particular embodiment of the 100 invention illustrated, the semaphore signal 8 and the upper arm of signal 7 are assumed to be three-position signals, that is, these

signals have a vertical or 90° position, indicating "clear" or that the track ahead is unoccupied and an approaching train may proceed at full speed; an inclined or 45° position indicating "caution" or that a train may proceed at a limited speed; and a horizontal or zero degree position indicating "stop" or "danger." However, this invention is fundamentally in no wise dependent upon three-position signals, and may be used without material change or modification with two-position signals. The lower arm of signal 7 is assumed to be a two-position signal, that is, this signal has an inclined or 45° position indicating to an approaching train that it is to take the siding S; and a horizontal or zero degree position indicating that the switch S¹ for the siding S is in the "normal" position and that the siding is either occupied or that an approaching train is to take the main track providing the upper arm of the signal 7 so indicates.

Associated with each of the arms 7¹, 7² and 8¹ are circuit controllers which are represented on the drawing according to established convention, said circuit controllers being designated 9 and 10 for arm 7¹; 11 and 12 for arm 7² on signal 7; and 13 for arm 8¹ on signal 8. Each of these circuit controllers are capable of a movement, the angular degree of which corresponds to the angular degree of movement of the respective arms with which said circuit controllers are associated. The circuit controllers 13 and 10 are closed during the movement of the corresponding arm from its vertical or proceed position to its inclined or caution position and are open when said arms are in their horizontal or "danger" positions. The circuit controller 9 is closed only in the horizontal position of the arm 7¹ and being open in each of the other two positions of said arm 7¹. The circuit controller 11 for the arm 7² is closed in the horizontal position of said arm and open in its operated position, whereas the circuit controller 12 for the same arm 7² is open in the horizontal position of the arm and closed in its operated position. The exact extent of angular movement of the corresponding signal during which said circuit controllers are operated, is dependent upon the operating characteristics of the signal and its controlling relays, the purpose of these circuit controllers and relays being hereinafter more fully set forth.

When the switch points S¹ of the siding S are lined up, as shown in the drawing, for traffic over the main stretch of track, the switch is said to be in the "normal" position, whereas, when the said switch points are lined up so that traffic will be over the siding S, the switch is said to be in the "reverse" position. Hereinafter, for convenience, when it is necessary to refer to the

different positions of the switch, they will be termed "normal" and "reverse" positions.

Associated with the switch for the siding S and operatively connected thereto is a circuit controller represented on the drawing by the letter C. This circuit controller consists of two pairs of fixed contacts represented diagrammatically on the drawing and designated by the numerals 14 and 15; 70 and 16 and 17, respectively, together with a movable contact 18 which is adapted, when the switch is in the "normal" position, to bridge the contacts 16 and 17 and complete a circuit which may be traced therethrough; 80 and likewise when the switch is reversed the contacts 14 and 15 will coat with the movable contact 18 in a similar manner. This circuit controller as preferably constructed is fully shown and described in the Patent 85 Number 1,169,957, granted to William S. Henry, filed February 1, 1916.

Also associated with the switch S¹ of the siding S, and operatively connected thereto, is an electrically operated switch machine 90 for throwing the switch from its "normal" to its "reverse" position or vice-versa and is represented generally on the drawing by the letter B. This switch machine consists generally of a motor armature 19 together with its field 20; a circuit controller 21; and a pole changer 22. The switch machine as shown in the drawing is in its "normal" position of the switch. The circuit controller 21 consists of two pairs of fixed contact springs diagrammatically represented on the drawing and designated by the numerals 23 and 24, and 25 and 26, together with two movable contacts 27 and 28. This circuit controller 21 is so designed that when 105 the switch is in the "normal" position, the movable contact 28 is in contact with the contact springs 25 and 26, whereas as soon as the switch machine B starts to move the switch S¹ of the siding S from its "normal" 110 to its "reverse" position, the movable contact 28 will be moved out of contact with the contact fingers 25 and 26. During this movement, however, the movable contact 27, which is mounted on the same block and 115 moves with the movable contact 28, is not moved far enough to coat with the contact springs 24 and 23, and consequently the movable contacts 27 and 28 will assume a position midway between the two pairs of 120 contact springs until the final movement of the switch machine B, whereupon the movable contacts 27 and 28 will be moved far enough for the movable contact 27 to make contact with the contacts 23 and 24. The 125 pole changer 22 consists of two pairs of fixed contact springs which are diagrammatically represented on the drawing and designated by the numerals 30 and 31; and 32 and 33, together with two movable con- 130

77 and front contact 78 of the line relay 39 in its upper position, wire 79, the motor for the arm 7¹ of the signal 7 and wires 80, 81, 82, 83, 84, 85, 86 and 62 back to the other 5 terminal of the battery 50.

The dropping of the armature 64 also 10 interrupts the circuit for the control of the 45° or "caution" position of the arm 7¹ of the signal 7, said circuit being traced as 15 follows:

Circuit number three.

Commencing at one terminal of the battery 50, wires 52 and 65, armature 66 and front 15 contact 67 of line relay 38 in its upper position, wire 68, armature 64 and front contact 20 69 of the track relay 6 in its upper position, wire 70, armature 71 and front contact 72 of the track relay 5 in its upper position, 25 wire 73, contacts 25, 28 and 26 of the circuit controller 21 of the switch machine B in its normal position, wire 74, contacts 16, 18 and 17 of the switch circuit controller C in its normal position, wires 75 and 87, the motor 30 for the signal arm 7¹ of the signal 7, wires 80, 81, 82, 83, 84, 85, 86, and 62 back to the other terminal of the battery 50.

From the circuits, numbers two and three just traced it will be apparent that as soon 35 as a train enters the track section *c*, the 90° and the 45° control circuits for the arm 7¹ of the signal 7 are interrupted, so that said arm 7¹ will drop by gravity to its horizontal or danger position, thus guarding 40 the train which is in the track section *c* from approaching trains moving in the same direction, that is, in the direction indicated by the arrow *e*.

When the upper arm 7¹ of the signal 7 45 moves to its zero degree or danger position, the circuit controller 10 which is operatively connected to said arm 7¹, will also be moved to a position corresponding to said signal arm 7¹, thus interrupting the circuit 50 which normally energizes the semaphore indicator 47 in the operating station A, said circuit being as follows:

Circuit number four.

50 Commencing at one terminal of the battery 50, wires 52, 53, 54, 55, 56, 88 and 89, armature 10¹ of the circuit controller 10 for the signal arm 7¹, wire 90, front contact point 91 and armature 92 of the line relay 38 in its upper position, wire 93, the right-hand knife of the control switch 41, pole 55 42 of said switch 41, wire 94, indicator 47 and wires 95, 96, 61 and 62 back to the other terminal of the battery 50.

60 Since the circuit just traced has been interrupted at the circuit controller 10, the indicator 47 will become deenergized and its blade will assume a position corresponding to that of the arm 7¹ of the signal 7, that 65 is, the zero degree or danger position, there-

by advising the operator in the station A that the arm 7¹ of the signal 7 has operated and has assumed its zero degree or danger position.

As the train in question proceeds in the 70 direction indicated by the arrow *e* and passes out of the track section *c* and enters the track section *b*, it causes the deenergization of the track relay 5. The dropping of the armature 71 of the track relay 5 75 opens another break in the circuits, numbers two and three for the 90° and 45° controls, respectively, of the arm 7¹ of the signal 7, so as to hold said arm 7¹, governing traffic in the direction stated, in its danger or stop 80 position.

As soon as the train has passed out of the track section *c*, the track relay 6 will again become energized in the well known manner and its armatures 51, 63 and 64 will be 85 again picked up. The picking up of the armature 51 causes circuit number one to be reestablished, thus causing the disk indicator 48 to again become energized which will indicate to the operator that the track 90 section *c* is unoccupied. However, since the track relay 5 is deenergized at this time, the picking up of the armature 64 does not reestablish circuits, numbers two and three for the signal arm 7¹ and since the signal 95 arm 7¹ remains in its danger position the circuit controller 10 will remain in a corresponding position, consequently holding the indicator 47 in its danger position.

As the train in question proceeds in the 100 direction indicated by the arrow *e* and passes out of the track section *b* and enters the track section *a*, the arm 8¹ of the signal 8 will assume its danger position, for reasons well known to those skilled in the art 105 of railway signaling, and will cause its circuit controller 13 to assume a corresponding position. When the circuit controller 13¹ moves to the zero degree position a circuit which normally energizes the line relay 39 110 will be interrupted, said circuit being traced as follows:

Circuit number five.

Commencing at one terminal of the battery 115 49, wires 104 and 105, contact strip 13² and armature 13¹ on circuit controller 13 in its 90° or 45° positions, wire 106, relay 39, wires 107, 82, 83, 84, 85, 86, 61, 96, 108 and 109 back to the other terminal of the battery 49.

The interrupting of the circuit just traced causes the line relay 39 to be deenergized and its armature 77 to drop. The dropping of the armature 77 makes another opening 125 in the circuit number two for the 90° control of the arm 7¹ of signal 7.

After the train passes out of the track section *b*, the track relay 5 will again become energized in the well known manner 130

tacts 29 and 29¹, each being adapted to make contact at times with one pair of said fixed contact springs, their movement being governed by the movement of the switch machine. For a further and more detailed description of the construction and operation of this switch machine, reference may be had to the application of Winthrop K. Howe, William S. Henry and Fred N. Hall, Serial Number 64,138, filed November 29, 1915.

10 A crank arm 34 is usually supplied with the switch machine for use when it is necessary to operate the switch S¹ manually as is sometimes the case, as for example, when 15 a maintainer desires to clean the switch points. Provision is usually made for housing this crank arm, and this housing is represented diagrammatically on the drawing as a box D which is conveniently located near the switch machine. The box D contains a pair of contact springs 35 and 36 rigidly fastened therein and between which the crank arm 34 makes electrical contact and is also securely held, for reasons which 25 will be hereinafter more fully explained.

Associated with the signal 7 is a group of relays hereinafter called line relays and designated on the drawing by the numerals 37, 38 and 39, the functions of which will be later 30 more fully explained. Another relay, designated by the numeral 40, is also associated with the signal 7 and will be hereinafter termed a detector relay for the reason that it insures that the switch machine B cannot 35 be operated unless both arms 7¹ and 7² of the signal 7 are in the horizontal or danger position, all of which will be clearly set forth hereinafter. Also associated with the signal 7 is a suitable source of electrical 40 current, as a battery, said battery being designated by the numeral 50.

Located at a point remote from the switch S¹ of the siding S is a tower or operating station represented diagrammatically on the 45 drawing by a dotted square and designated by the letter A. Conveniently located within the operating station A is a control switch 41 for controlling the "normal" and "reverse" positions of switch S¹, and this 50 switch is shown on the drawing for the sake of simplifying the explanation as a double pole double throw switch although it might be a lever of an interlocking machine or some other form of a device suitable for 55 performing the necessary functions. Also conveniently located in the operating station A is a group of indicators of any suitable or well known type, familiar to those skilled in the art of railway signaling, which 60 are designated by the numerals 46, 47 and 48. The indicators 46 and 47 illustrated are of the semaphore type and are associated with the signal 7 for repeating the indications of the arms of said signal 7 to the operator in the station A; whereas the indica-

tor 48 is shown as a disk type indicator, so that it can easily be distinguished from 46 and 47, and is associated with the track relay 6 for the track section c to indicate to the operator in the station A the presence of 70 a train on the track section c. A battery 49 is also located in the operating station A to provide a suitable source of electrical current.

Operation.

75

With all the devices in the positions as shown in the drawing, and with no train on the track sections a, b, c or d, the parts thereof may be considered to be in their "normal" positions and the route lined up for traffic over the main stretch of track in the direction indicated by the arrow e.

Assume that a train moving in the direction indicated by the arrow e, enters the 85 track section d; accepts the upper arm "clear" signal of the signal 7; and passes onto the track section c. When said train enters the track section c, the track relay 6 will be deenergized, as will be clearly understood by those skilled in the art of railway signaling, and its armature 51 will drop and interrupt the circuit which normally energized the coils of the disk indicator 48, said circuit being traced as follows:

Circuit number one.

Commencing at one terminal of the battery 50, wires 52, 53, 54, 55, 56 and 57, armature 51 of the relay 6 in its energized condition, front contact 58 of the relay 6, wire 59, through the coils of the indicator 48, wires 60, 61 and 62 back to the other terminal of the battery 50.

From the circuit just traced it can be seen 105 that the indicator 48 in the operating station A will drop and will notify the operator of the presence of the train in the track section a.

The deenergization of the track relay 6 110 also causes its armature 64 to drop and interrupt the circuit which, normally closed, operates the arm 7¹, of the signal 7, to its 90° or "clear" position, said circuit being as follows:

Circuit number two.

Commencing at one terminal of the battery 50, wires 52 and 65, armature 66 and front contact 67 of the line relay 38 in its upper 120 position, wire 68, armature 64 and front contact 69 of the track relay 6 in its upper position, wire 70, armature 71 and front contact 72 of the track relay 5 in its upper position, wire 73, fixed contact 25, movable contact 125 28 and fixed contact 26 of the circuit controller 21 of the switch machine B in its normal position, wire 74, contacts 16, 18 and 17 of the switch circuit controller C in its normal position, wires 75 and 76, armature 130

and its armature 71 will be again picked up, thereby closing an opening which was made in circuits, numbers two and three. However, since the line relay 39 is deenergized, circuit number two for the 90° control of signal arm 7¹ cannot be closed but the circuit number three for the 45° control of signal arm 7¹ becomes effective and the said arm 7¹ is raised to its 45° position thus indicating to an approaching train that it may proceed but at limited speed. As soon as the arm 7¹ of the signal 7 is raised to its 45° position the armature 10¹ on the circuit controller 10 will also be raised to a corresponding position and as circuit number four for indicator 47 is closed from the 45° to the 90° positions of the signal, said circuit will be again established and the indicator 47 will be raised to a corresponding position thus notifying the operator that track section b is clear.

When the train in question has passed out of track section a, signal 8 will assume its 45° position for reasons understood by those skilled in the art of railway signaling and as circuit number five is closed from the 45° to the 90° positions of the signal 8, said circuit will be reestablished causing the line relay 39 to become energized and its armature 77 picked up. When armature 77 is picked up the gap in circuit number two for the 90° control of arm 7¹ is closed thereby permitting said arm 7¹ of signal 7 to raise to its 90° or clear position.

The passing of a train over the main stretch of track having been described and the operation of the signals and various devices in connection with the movements thereof having been fully pointed out, it will now be apparent to those skilled in the art of railway signaling that at times it becomes necessary for the operator in the station A to clear the main track in order that one train may pass another or obviously for any other reason and to do this said operator takes advantage of the siding S.

When said operator wishes a train to take the siding S and the devices are in their normal positions as shown in the drawing, he throws the switch 41 from the "normal" position as shown in the drawing to a "reverse" position causing said switch 41 to break contact with poles 42 and 43 and to make contact with poles 44 and 45. The throwing of the switch 41 from its "normal" to its "reverse" position interrupts a circuit which normally energized the line relay 38, said circuit being as follows:

Circuit number six.

Commencing at one terminal of the battery 49, wires 104 and 110, pole 43 and the left-hand knife of switch 41, wire 111, armature 112 and back contact 113 of line relay 37 in its lower position, wire 114, the coils of line

relay 38 and wires 115, 83, 84, 85, 86, 61, 96, 108 and 109 back to the other terminal of battery 49.

The interrupting of the circuit just traced causes the line relay 38 to become deenergized and its armatures 116, 66 and 92 to drop. The dropping of the armatures 66 interrupts circuits, numbers two and three for the 90° and 45° controls, respectively, of the upper arm 7¹ on the signal 7 causing said signal arm 7¹ to drop to its zero degree or danger position. The dropping of the armature 92 of the line relay 38 interrupts circuit number four for energizing the semaphore indicator 47 causing it to assume a corresponding position to the arm 7¹ of the signal 7. The dropping of the armature 92 of the relay 38 also causes a circuit to be established for energizing the line relay 37, said circuit being traced as follows:

Circuit number seven.

Commencing at one terminal of the battery 49, wires 104, 110 and 117, pole 45 and the righthand knife of switch 41, wire 93, armature 92 and back contact 118 of line relay 38 in its lower position, wire 119, the coils of relay 37 and wires 120, 84, 85, 86, 61, 96, 108 and 109 back to the other terminal of battery 49.

The circuit just traced causes the line relay 37 to be energized and its armatures 121, 122 and 112 to be picked up.

When the signal arm 7¹ drops to its zero degree or danger position due to the interrupting of its circuits, numbers two and three as above stated, the armature 9¹ of the circuit controller 9 for said signal arm 7¹ will also drop to its zero degree position, thus establishing a circuit for energizing the detector relay 40 and causing its armatures 123 and 124 to be picked up, said circuit being traced as follows:

Circuit number eight.

Commencing at one terminal of the battery 50, wires 52, 53, 54, 55, 56, 88, 89, and 97, armature 9¹ of circuit controller 9 in its zero degree position, wire 98, armature 11¹ of circuit controller 11 in its zero degree position, wire 99, front contact 100 and armature 63 of the track relay 6 in its upper position, wire 101, contact 35, crank 34 and contact 36 of the crank housing D, wire 102, detector relay 40 and wires 103, 86 and 62 back to the other terminal of the battery 50.

When the line relay 38 is deenergized and the line relay 37 and the detector relay 40 are energized, a circuit for operating the motor of switch machine B to throw switch S¹ from its normal to its reverse position is established and may be traced as follows:

Circuit number nine.

Commencing at one terminal of the battery 130

- 50, wires 52, 53, 54 and 125, front contact point 126 and armature 121 of line relay 37 in its upper position, wires 127 and 128, armature 19 of the motor for switch machine 5 B, wires 129 and 130, armature 116 and back contact 131 of line relay 38 in its lower position, wire 132, contacts 33, 29¹, and 32 of the pole changer 22, of the switch machine B, in its normal position, wires 133 and 134, field coil 20 of the motor for switch machine B, wire 135, armature 123 and front contact 136 of the detector relay 40 in its upper position, wires 137, 85, 86 and 62 back to the other terminal of the battery 50.
- 15 With energy applied to the motor of the switch machine B, as shown by the circuit just traced, said motor will operate in a manner to cause said switch machine B to throw the switch S¹, for the siding S, from 20 its "normal" position, or the position shown in the drawing, to a "reverse" position, all of which is fully described in the above mentioned application Number 64,138, so that the switch S¹ will be lined 25 up for traffic over the siding S in the direction indicated by the arrow e. When the switch S¹ is fully thrown to its reverse position and locked therein, the final movement of the switch machine B causes the movable 30 contacts 29 and 29¹ of the pole changer 22 to be thrown to a reverse position where movable contact 29 makes contact with fixed contacts 30 and 31 and the electrical connection which was made by movable contact 35 29¹ with fixed contacts 32 and 33 will be broken, thus interrupting circuit number nine just traced for furnishing energy to the motor of switch machine B.
- 40 The moving of the switch points S¹ from their "normal" to their "reverse" position causes the switch circuit controller C, which is directly connected to said switch points S¹, to operate in the well known manner as described in the above mentioned Patent 45 Number 1,169,957, and to cause movable contact 18 thereof to break contact with fixed contacts 16 and 17 of said circuit controller C and to make contact with fixed contacts 14 and 15 of the circuit controller C. The operation of the circuit controller C, as just described, opens another break in circuits, numbers two and three for the 90° and 45° position of arm 7¹ of signal 7, keeping said signal in the danger position and 55 causing a circuit to be established for moving signal arm 7² of signal 7 to its operated or 45° position, thus denoting to a train approaching said signal in the direction indicated by the arrow e that the route is 60 set up for traffic over the siding S, said circuit being traced as follows:

Circuit number ten.

Commencing at one terminal of battery 50,

wires 52, 53, and 138, armature 122 of line 65 relay 37 in its upper position, front contact 139 of said relay, wire 140, contacts 24, 27 and 23 of circuit controller 21 in its reverse position, wire 141, contacts 14, 18 and 15 of switch circuit controller C in its reverse position, wire 142, signal motor for arm 7² of signal 7, wires 143, 81, 82, 83, 84, 85, 86, and 62 back to the other terminal of battery 50.

When the signal arm 7² moves to its operated position, as just described, its circuit controller 12 assumes a corresponding position and there is established a circuit for energizing the indicator 46 in the operating station A, said circuit being traced as follows:

Circuit number eleven.

Commencing at one terminal of the battery 50, wires 52, 53, 54, 55, 56 and 88, armature 85 12¹ of circuit controller 12 for signal arm 7² in its operated position, wire 144, front contact 145 of line relay 37, armature 112 of said relay 37 in its upper position, wire 111, lefthand knife of operating switch 41, 90 pole 44 of said switch in its reverse position, wire 146, indicator 46, wires 147, 108, 96, 61 and 62 back to the other terminal of battery 50.

From the circuit just traced it will be apparent that the indicator 46 will be operated to a position corresponding to the operated position of the lower arm 7² of the signal 7, thus notifying the operator in station A that the switch S¹ for the siding S has been moved to its "reverse" position and that the route is set up for traffic over the siding S in the direction indicated by the arrow e.

When the arm 7² of the signal 7 is moved to its operated position, its circuit controller 11 also assumes a corresponding position, thus causing a break to be made, by the moving of the armature 11¹ of said circuit controller 11; in circuit number eight. The interrupting of the circuit number eight causes the deenergization of the detector relay 40 and its armatures 123 and 124 are dropped. The dropping of the armature 123 makes another break in the circuit number nine for operating the motor of switch machine B. The dropping of the armature 124 establishes a shunt path around the armature 19 of the motor, for the switch machine B, thus making it impossible to apply energy to operate said motor until the detector relay 40 has been again energized and its armatures 123 and 124 picked up.

From the foregoing description, it will be seen that the detector relay 40 can be 125 energized, only when both arms 7¹ and 7² of the signal 7 are in the danger positions and there is no train in the track section e,

therefore when the detector relay 40 is de-energized circuit number nine is broken and no energy can be supplied to operate the motor of the switch machine B, which insures that the switch S^1 cannot be thrown by the operator in station A until he has placed both of the signal arms 7^1 and 7^2 in the danger position and until the track section c is entirely clear; and if a train has 10 taken the siding S, it must have passed the fouling point X of said siding before the switch can be again operated.

Assume now that the train which the operator wishes to take the siding S and for which he has reversed switch S^1 , has entered track section c . As soon as said train enters said track section c , circuit number one will be interrupted, for reasons before stated; and disk indicator 48 will be 20 again deenergized and will inform the operator of the presence of a train in said track section c . As soon as the train in question has taken the siding S and proceeded thereon far enough to have passed 25 the fouling point X, then, the track section c being clear, the track relay 6 will be picked up, as is well known to those skilled in the art, and circuit number one will be reestablished causing said indicator 48 to become 30 again energized thereby informing the operator that the train has cleared track section c and has passed far enough on the siding to permit a train to pass safely along the main track. The operator therefore 35 throws the operating switch 41 from its reverse to its normal position, or the position shown in the drawing.

When the operating switch 41 is thrown from its reverse to its normal position as 40 stated, certain circuits are established and others are broken and the operation of the various devices occurs in sequence, as the operation of certain of the devices depends for the sake of safety upon the operation 45 of certain of the other devices. The throwing of the switch 41 interrupts circuit number seven for energizing the line relay 37 and its armatures 121, 122 and 112 are dropped. The dropping of the armature 50 122 interrupts circuit number ten for operating the arm 7^2 of signal 7 to its 45° or operated position and said signal arm 7^2 falls to its danger position which will be clearly understood by those skilled in the 55 art. The dropping of armature 112 on relay 37 and the moving of circuit controller 12 for signal arm 7^2 causes two openings to be made in the circuit number eleven, for energizing indicator 46, said indicator assuming a position corresponding to that of signal arm 7^2 on signal 7. When the circuit controller 11 of signal arm 7^2 assumes its zero degree position, circuit number eight, for energizing the detector relay 40, is re-

established and armatures 123 and 124 are 65 picked up.

When armature 112 on relay 37 dropped to its lower position upon the deenergization of line relay 37, circuit number six, which was previously traced through line 70 relay 38 for energizing said relay 38, was reestablished and the armatures 116, 66 and 92 of said relay were picked up. The picking up of armature 116 establishes a circuit for operating the motor of switch machine B to cause said switch machine B to operate in a manner to throw switch S^1 from its reverse position to its normal position or the position shown in the drawing, said circuit being traced as follows: 75

80

Circuit number twelve.

Commencing at one terminal of the battery 50, wires 52, 53, 54, 55 and 148, front contact 149 on relay 38, armature 116 of said 85 relay in its upper position, wires 130 and 129, armature 19 of switch machine B, wires 128 and 127, armature 121 of relay 37 in its lower position, back contact 152 of said relay, wire 150, contacts 31, 29 and 30 of the 90 pole changer of switch machine B in its reverse position, wires 151 and 134, field coil 20 of the motor of switch machine B, wire 135, armature 123 of detector relay 40 in its upper position, front contact 136 of said 95 relay, wires 137, 85, 86 and 62 back to the other terminal of battery 50.

When the switch machine B starts to move, its circuit controller 21 is moved to its middle position, as previously described, 100 thus making a second break in circuit number ten for operating signal arm 7^2 and preventing said signal arm 7^2 from being changed from its danger position while the switch S^1 is being thrown, even though the 105 line relay 37 should for any reason become energized during the movement of said switch.

The movement of the switch points S^1 causes the switch circuit controller C to be 110 moved from its reverse to its normal position and in so doing makes a third break in the circuit number ten for operating the signal arm 7^2 on the signal 7, the purpose of which will be later explained, and when the 115 switch points S^1 are in their full normal position, the switch circuit controller through the medium of movable contact 18 causes one of the breaks that had been made in circuits, numbers two and three to be 120 closed. The final movement of the switch machine B after the switch S^1 has been moved to its full normal position and locked, causes the circuit controller 21 of said switch machine B to be thrown to its 125 full normal position, thereby completely re-establishing circuit number two for operating signal arm 7^1 to its 90° or clear position.

Simultaneously with the throwing of the circuit controller 21 to its full normal position, the pole changer 22 of the switch machine B is moved to its full normal position, 5 thus interrupting circuit number twelve for operating the motor of switch machine B to its normal position.

When the signal arm 7¹ of the signal 7 is operated to the clear position as above described 10 its circuit controller 9 will assume a corresponding position and the circuit number eight, previously traced through said circuit controller 9 in its zero degree position for energizing the detector relay 15 40, will be interrupted and the armatures 123 and 124 of said detector relay 40 will be dropped. The dropping of the armature 124 establishes a shunt path around the armature 19 of the motor for the switch machine B 20 which as has been explained prevents current from being applied to the said motor until said armature 124 has been picked up. The dropping of the armature 123 of the detector relay 40 opens another break in the circuit 25 number twelve for operating the motor of the switch machine B when the switch S¹ is being moved to its normal position. This last break in the said circuit number twelve insures that before energy can be applied to 30 operate the motor for the switch machine B, the detector relay 40 must be energized. This is done as has been explained by putting both of the signal arms 7¹ and 7² on the signal in the danger position. As soon as the 35 signal arm 7¹ is moved to its clear position as explained above, its circuit controller 10 causes to be reestablished the circuit number four for energizing the indicator 47 in the operating station A, thus notifying the operator 40 that the main trackway has been cleared.

From the foregoing description it will be noted that when it is necessary for the operator in station A to throw the switch S¹ for 45 the siding S from normal to reverse or vice-versa, it is first necessary to have both of the signal arms 7¹ and 7² of the signal 7 in the danger position and before said signals can be again cleared, the switch S¹ must be in 50 the position desired; the switch circuit controller C must be in a position corresponding to the position of switch S¹, the switch machine D must have been operated to the desired position and locked so that its circuit 55 controller 21 is in a position corresponding to the position of switch S¹ and the switch circuit controller C; and the line relay governing the switch function must be energized and the opposite line relay deenergized. 60 Therefore it will be apparent that should a connection become broken between the switch machine A and the switch S¹, or between the switch circuit controller C and the switch S¹ or if one of the relays for any cause should 65 fail to operate correctly or obviously if for

any other reason the switch should fail to operate correctly, the signals guarding said switch will operate on the side of safety and will remain in the danger position.

From the foregoing description it will be 70 apparent that when the line relay 38 is energized, the line wire 111 is included in the circuit for energizing said relay 38, whereas, the line wire 93 is used to carry the indication current and in a like manner when the line relay 37 is energized, the line wire 93 is included in the circuit for energizing said relay 37, whereas, the line wire 111 is used to carry the indication current. It will therefore be seen that the line wires 93 and 75 111 serve a double purpose and will result in a great saving in the amount of line wire used.

In cases of emergency, if it becomes necessary for the switch to be thrown manually, 80 this may be done by inserting the crank arm 34 in a place provided therefor on one end of the shaft of the armature 19 of the motor for switch machine B. As a precautionary 85 measure to prevent power from being applied to the motor from the operating station A, when said switch machine is being operated manually, the crank arm 34 and said contacts 35 and 36 are included in circuit 90 number eight for energizing the detector relay 40. It will therefore be seen that, when the crank arm 34 is removed from its housing D, circuit number eight will be interrupted and for reasons hereinbefore explained it will be impossible to apply current 95 to the motor of switch machine B.

Various changes may be made in the particular arrangement of circuits and controlling devices shown and described without departing from the invention or the physical embodiment thereof illustrated, and also this invention may be applied to other signaling systems. Also, although the particular embodiment of the invention shown is designed 100 to be operated by direct current, simple modifications apparent to those skilled in the art of railway signaling, may be made where alternating current may be used as an operating medium.

Although I have particularly described 105 the construction of one physical embodiment of my invention, and explained the operation and principle thereof; nevertheless, I desire to have it understood that the form selected is merely illustrative, but does not exhaust 110 the possible physical embodiments of the idea of means underlying my invention.

What I claim as new and desire to secure by Letters Patent of the United States, is:

1. In a traffic controlling system for railways, in combination: a stretch of track divided into blocks; a switch associated with one of said blocks; an electrically operated switch machine; circuits for operating said switch machine to its normal and reverse 125 130

- positions; means controlled alternately from a remote point or station for governing said circuits separately; and other means controlled automatically by the track circuit for the block adjacent to said switch for checking the circuits governed by said last mentioned means.
2. In a traffic controlling system for railways, in combination: an electrically operated switch machine having a normal and a reverse position; a local source of energy for operating said switch machine; two relays controlled alternately from a remote point or station; a circuit for each position of said switch machine governed by both of said relays; a third relay controlled automatically; and means controlled by said third relay and included in said circuits for said switch machine for checking the two first mentioned relays.
3. In a traffic controlling system for railways, in combination: a stretch of track divided into blocks; a switch associated with one of said blocks; an automatic block signal for governing traffic over each of said blocks; separate signaling means associated with said signal for indicating the position of the switch; an electrically operated switch machine for operating said switch; circuits for operating said switch machine to move said switch; means controlled from a remote point or station for controlling each of said circuits separately; a circuit for controlling said separate signaling means, said circuit being controlled jointly by said switch machine and said means; and other means for governing the operating circuits for said switch machine, said means being controlled automatically by the track circuit for the block adjacent to said switch and dependent upon the position of both the signal governing that block and also the signaling means governing the switch.
4. In a traffic controlling system for railways, in combination: a stretch of railway track divided into insulated track circuit sections; a track relay and a source of current for each track circuit section; a switch for said stretch of track having a normal and a reverse position; a signal for each track section and for said switch; an electrically operated switch machine for operating said switch to each of said positions; a local source of energy for operating said switch machine; circuits including said source of energy for operating said switch machine to move said switch to each of its positions; means controlled from a remote point or station for controlling each of said circuits separately; means controlled by said signals and one of said track sections for controlling each of said circuits for said switch machine; an indicating means located at said remote point or station and controlled by said first mentioned means for indicating the operated condition of said signals and said switch.
5. In a traffic controlling system for railways, in combination: an electrically operated switch machine; circuits for operating said switch machine automatically to its normal and reverse positions; means controlled from a remote point or station for governing said operating circuits separately; means for checking each of said operating circuits; a crank arm for manually operating said switch machine to either of its positions independently of said automatic operating means; and a circuit for automatically controlling said checking means, said circuit including an arrangement of contact devices for holding said handle when not in use, whereby a removal of the handle to perform said manual operation causes a break in the controlling circuit for said checking means and thereby prevents an accidental application of power to said switch machine when said device is being operated manually.
6. In a traffic controlling system for railways, in combination: a stretch of track divided into blocks; a switch associated with one of said blocks; an automatic block signal having different operated positions, associated with each of said blocks; a separate signaling means for indicating the position of said switch, said means also having different operated positions; circuit controllers associated with said signals and said signaling means, adapted to be operated thereby to positions corresponding with the positions of their respective signals; an electrically operated switch machine; circuits for operating said switch machine to move the switch to its normal and reverse positions; means controlled from a remote point or station for controlling each of said circuits separately; and other means controlled automatically by the track circuit for the block adjacent to said switch and dependent upon the position of the circuit controllers of the signal governing said adjacent block and also of the signaling means whereby the operation of the switch machine is prevented unless the said adjacent block is clear and the signals governing both the main track route and the turn out route are set to indicate danger.
7. In a traffic controlling system for railways, in combination: an electrically operated switch machine having a normal and a reverse position and comprising a motor for operating said switch machine to each of its positions; a circuit for operating said motor for each position of said switch machine; a local source of energy included in said circuits; a pole changer included in said switch machine and governed by said motor for controlling said circuits; a shunt circuit for short circuiting the armature of said motor after current has been cut off by the

action of said pole changer; and means controlled from a distant point for controlling said first mentioned circuits and said shunt circuit.

- 5 8. In a traffic controlling system for railways, in combination: a stretch of track divided into blocks; an outlying switch associated with one of said blocks; signals for governing traffic over said blocks and signaling means associated with the signal for the block adjacent to said switch for indicating the position of said switch; an electrically operated switch machine for operating said switch; two control relays; means for controlling said relays from a remote point or station, the energizing circuit of each of said relays including a back contact of the other of said relays; operating circuits for said switch machine, said signal and said signaling means, controlled automatically by said relays; and means controlled automatically by the track circuit for said adjacent block for checking said operating circuits, said means being dependent upon the track circuit of the section adjacent to said switch and the signals for both said switch and its adjacent section being in their danger position.

9. In a traffic controlling system for railways, in combination: a stretch of track divided into blocks, a signal associated with each of said blocks and operated automatically by the track circuits for said blocks, said signals being biased to a danger position and having two operated positions; circuit controllers associated with each of said signals having circuit controlling positions corresponding with the positions of their respective signals; a switch associated with one of said blocks; an electrically operated switch machine; circuit controlling means associated with said switch machine and operated thereby; separate signaling means associated with the signal governing the block adjacent to said switch for indicating the position of the switch; a circuit controller associated with said signaling means and operated thereby; normal and reverse operating circuits for operating said switch machine to move said switch, said circuits being controlled by the circuit controller on said switch machine; circuits controlled by the circuit controller on said switch machine for operating the block signal governing the block adjacent to said switch and also for governing the signaling means for said switch; circuit controlling means included in said signal circuits and governed by the movements of the switch points; means controlled from a distant point or station for governing the normal and reverse operating circuits and also each

of said signal circuits; and means for automatically checking the circuits governed by said last mentioned means.

65

10. In a traffic controlling system for railways, in combination: a stretch of track divided into blocks; an outlying switch associated with one of said blocks; an automatically controlled signal for governing traffic over the block adjacent to said switch; separate signaling means associated with said signal for indicating the position of said switch; an electrically operated switch machine for moving said switch; normal and reverse operating circuits for said switch machine; circuits for operating said signal and said signaling means to their different indicating positions; two relays controlled alternately from a remote point or station for controlling the normal and reverse operating circuits for said switch machine and also the operating circuits for said signal and said signaling means; indicating means for repeating at said remote point or station the indications of said signal and said signaling means, said means being automatically controlled by said relays; and other means automatically controlled by the track circuit for the block adjacent to said switch for checking the circuits controlled by said relays.

80

11. In a traffic controlling system for railways, in combination: a track section provided with a track circuit and a track relay; a switch associated with said track section; an electrically operated switch machine for moving said switch; normal and reverse operating circuits for said switch machine; and means controlled automatically by the track relay for preventing the closing of either the normal or reverse operating circuits when said track relay is de-energized by the presence of a train on said track section.

105

12. The combination with an outlying switch associated with a block provided with a track circuit and a track relay, in an automatic block signaling system; of an automatic block signal for said block, separate signaling means associated with said signal for indicating the positions of the switch; an electrically operated switch machine for operating said switch to its normal and reverse positions, operating circuits for said switch machine; said signal and said separate signaling means; means controlled from a remote point or station for governing said operating circuits and means controlled automatically by said track relay for checking each of said operating circuits.

110

CHARLES S. BUSHNELL.
